UNITED STATES PATENT OFFICE.

EDWARD ALBRECHT AND WALTER H. SCHUSSLER, OF PHILADELPHIA, PENNSYLVANIA.

HOISTING AND DUMPING VEHICLE.

1,377,611.

Specification of Letters Patent.

Patented May 10, 1921.

Application filed March 25, 1919. Serial No. 285,001.

To all whom it may concern:

Be it known that we, EDWARD ALBRECHT and WALTER H. SCHUSSLER, citizens of the United States, residing in the city and 5 county of Philadelphia, State of Pennsylvania, have invented a new and useful Hoisting and Dumping Vehicle, of which the following is a specification.

Our invention comprehends a novel construction and arrangement of a hoisting and dumping vehicle wherein we eliminate the necessity of having working parts extending below the chassis or running gear of the vehicle, and wherein the number of 15 parts employed is reduced to a minimum.

It further comprehends a novel vehicle body of the character stated, and novel actuating means for it, said body having its center of gravity the same when in raised 20 position as it is when in lowered position.

It further comprehends a novel vehicle body and novel means for raising and lowering it.

Other novel features of construction and 25 advantage will hereinafter more clearly appear in the detailed description of our invention.

For the purpose of illustrating our invention, we have shown in the accompanying drawing one form thereof which is at present preferred by us, since the same will be found in practice to give satisfactory and reliable results, although it is to be understood that the various instrumentalities of 30 which our invention consists can be variously arranged and that our invention is not limited to the precise arrangement and organization of these instrumentalities as herein shown and described.

40 Figure 1 represents in side elevation a vehicle of the motor driven type, in conjunction with which a hoisting and dumping body embodying our invention is employed.

45 Fig. 2 represents a section on line 2—2 of Fig. 3.

Fig. 3 represents a section on line 3—3 of Fig. 2.

50 Fig. 4 represents a section on line 4—4 of Fig. 3.

Fig. 5 represents a section on line 5—5 of Fig. 3.

Fig. 6 represents in side elevation another embodiment of our invention.

55 Fig. 7 represents a section on line 7—7

of Fig. 6. Fig. 8 represents in side elevation a portion of a side rail 3 seen in Fig. 6.

Similar numerals of reference indicate corresponding parts in the figures.

Referring to the drawings.

1 designates a vehicle of any desired construction. We have preferred to illustrate the vehicle as being of the motor driven type, but it is apparent that our invention can be employed in conjunction with any 65 desired type of vehicle irrespective of the means employed to move it. The chassis or running gear 2 may be of any desired or conventional type and as shown is provided with side rails 3 connected to it in any de- 70

sired manner and which if desired may be apertured as at 4 in order to decrease the weight. The sides are slotted as at 5 to form a bearing for anti-friction rollers 6 mounted at the ends of a shaft 7. The lower 75

ends of lifting bars 8 are loosely mounted on the shaft 7 and their upper ends are pivotally connected at 9 to the frame 10 of the vehicle body 11 which latter may be of any 80

desired construction. The bars 8 are braced 85 by reinforcing strips 12 preferably connected with each other as at 13. The rear portion of the frame 10 is provided with anti-friction rollers 14 which travel on the side rails 3. The chassis near the driver's 85

seat is provided with standards 15 in the form of channel beams which are secured at their lower ends to the chassis 2 and connected by cross braces 16 and cross bars 17. The standards 15 are provided with 90

spaced openings 18 to receive a stop rod 19 which has one end threaded and provided with a nut to retain it in position. The lower ends of the standard are connected by a rod 20 which carries a pulley 21, and a 95

similar rod 22 is provided at the upper end which carries a pulley 23. 24 designates a cable which has one end fixed to a pulley 25 fast on a winding shaft 26 journaled in the side rails 3. The shaft 26 is provided with a gear 27 which meshes with a pinion 28, fixed to a gear 29, suitably mounted and meshing with a pinion 30 on a shaft 31 adapted to be revolved either by hand or mechanically, and as shown its outer end 100 is shaped to receive a suitable handle 38. The shaft 31 has fixed to it a ratchet 32 with which co-operates a pawl 33 to prevent the unwinding of the winding shaft. The cable passes from the pulley 25 rear- 110

wardly and around the rear pulley 39 on the shaft 7, thence forwardly around the pulley 21, thence upwardly over the pulley 23, and then downwardly, and the end of 5 the cable is connected to an eye bolt 34 fixed to the frame 10 which carries the vehicle body.

The frame 10 at its forward end is provided with the anti-friction rollers 35 which 10 are guided in the channel bars 15.

In the embodiment seen in Figs. 6 and 7, the construction is the equivalent of that shown in the other figures. The standards 15 curve rearwardly at their upper ends and 15 the side rails 3 at their rear ends are provided with recesses 36 to receive the rear rollers carried by the body, and thus form a pivotal point for the upward movement of the forward end of the body. Arms 37 20 depend from the body to prevent lateral movement of it.

In the operation, it will be seen that when the winding shaft is revolved the front end of the body is elevated until it strikes the 25 stop rod and then the pull on the cable moves the shaft 7 forwardly, thereby causing the bars 8 to raise the rear portion of the body into an inclined or horizontal position as desired.

30 It will be apparent that in accordance with our present invention the wagon body can be made higher than is possible with the ordinary construction of hoisting and dumping body. This is of especial advantage since the wagon body can be raised to such height that the contents can be discharged directly into or received from a freight car, or any elevated container. The center of gravity of the body remains the 35 same, that is, it has the same relation with respect to the chassis when the body is in raised position as it does when the body is in its lowered or normal position. It will be seen that when the front end of the wagon 40 body is being raised it is accurately guided due to the anti-friction rollers carried by it which move in the channels of the standards 45 15. These standards and the manner in which the wagon body is connected with them 50 makes a very rigid construction, and prevents shaking or lateral movement of the body when it is in its elevated position. The raising bars 8 are pivoted near the center of gravity of the body, and toward the front 55 15 and when in their normal or collapsed condition, they do not extend below the chassis, the advantage of which is evident.

60 It will be seen that when the vehicle body is in its raised position the rollers at the lower end of the lifting bars are in rear of the center of gravity of the body, so that when the vehicle body is lowered the rear end of the body will always start to lower first.

65 It will be apparent from the foregoing

that in the present invention we have reduced to a minimum the number of parts which it is necessary to employ to effect the raising and lowering of the vehicle body, with consequent reduction in the amount of 70 friction created by the moving parts.

It will be apparent that the power required to raise the load is constant at any position of the vehicle body, which renders it easier to adjust the vehicle body to any 75 desired height.

It will now be apparent that we have devised a novel and useful hoisting and dumping vehicle which embodies the features of advantage enumerated as desirable in the 80 statement of the invention and the above description, and while we have, in the present instance, shown and described preferred embodiments thereof which will be found in practice to give satisfactory and reliable results, it is to be understood that they are 85 susceptible of modification in various particulars without departing from the spirit or scope of the invention or sacrificing any of its advantages.

Having thus described our invention, what we claim as new and desire to secure by Letters Patent is:—

1. In a hoisting and dumping vehicle, the combination with the chassis and its body, 95 of standards guiding the front end of said body, bars connected at their front ends to the body and having their rear ends slidably relatively to said chassis, anti-friction devices guided by said standards and carried 100 by the rear ends of said bars, a cable passing around said devices and having one end fixed to the front end of said body, and means to actuate said cable.

2. In a hoisting and dumping vehicle, the 105 combination with the chassis and its body, of standards on the chassis guiding the front end of the body, bars connected to the front end of said body, a shaft at the rear end of said bars and longitudinally movable relatively to said chassis, an upper and a lower cable engaging member mounted in said standards, a cable engaging member on said shaft, a winding shaft mounted on said chassis, and a cable passing from said winding shaft around the cable engaging means on said shaft, around said lower and upper cable engaging means of said standards, and connected to said body.

3. In a hoisting and dumping vehicle, the 120 combination of the chassis and its body, of standards on the chassis guiding the front end of the body, a stop on said standards in the path of movement of said body, a cable to raise the front end of said body, and 125 means controlled by said cable after the front end of said body is arrested by said stop to cause the rear end of said body to be raised.

4. In a hoisting and dumping vehicle, the 130

combination of the chassis and its body, of standards on the chassis guiding the front end of the body, an adjustable stop on said standards in the path of movement of said body, a cable to raise the front end of said body, and means controlled by said cable after the front end of said body is arrested by said stop to cause the rear end of said body to be raised.

5. In a hoisting and dumping vehicle, the combination of the chassis and its body, of standards curving upwardly and rearwardly from the chassis and in which the front end of the body is guided, bars connected with said body in front of its center of gravity, a shaft secured to said bars and guided in said chassis for limited longitudinal movement, cable engaging means on said standards and shaft, a cable passing around said means and connected to said body, and means to actuate said cable.

6. In a hoisting and dumping vehicle, the combination of the chassis and its body, of standards curving upwardly and rearwardly from the chassis and in which the front end of the body is guided, anti-friction devices at the rear of said body and supported by said chassis, bars connected with said body in front of its center of gravity, a shaft secured to said bars and guided in said chassis for limited longitudinal movement, cable engaging means on said standards and shaft, a cable passing around said means and connected to said body and means to actuate said cable.

7. In a hoisting and dumping vehicle, the combination with a chassis having side rails, of a body, standards rising from the chassis and guiding the front end of the body, anti-friction devices between said body and chassis, a bar secured to said body and slidably connected with said side rails, cable members on said standards, a cable for said members connected to the front end of said body and operatively connected with said bars to move them when the front end of the body is raised to a determined height, and actuating means for said cable.

8. In a hoisting and dumping vehicle, the combination with a chassis having side rails, of a body, standards rising from the chassis and guiding the front end of the body, anti-friction devices between said body and chassis, a bar secured to said body and slidably connected with said side rails, cable members on said standards, a cable for said members connected to the front end of said body and

operatively connected with said bars to move them when the front end of the body is raised to a determined height, said side rails 60 having means to form a pivotal connection with said anti-friction devices and actuating means for said cable.

9. In a hoisting and dumping vehicle, the combination with the chassis and side rails 65 carried by it, a body slidably mounted on said side rails, anti-friction devices between said body and chassis, standards extending upwardly from said body and having guide ways, means carried by the front end of the 70 body to engage said guide ways, an upper and a lower pulley on said standards, a cable passing around each pulley and connected with the front end of said body to raise it, and means co-operating with said pulley, 75 and with said cable to cause the rear end of said body to be raised after the front end has been elevated to a predetermined position.

10. In a hoisting and dumping vehicle, the 80 combination with the chassis having side rails, of a body loosely mounted on said side rails, standards rising from said chassis, an upper and a lower pulley mounted on said standards, bars connected at one end with 85 said body and at the other end having means in sliding engagement with said side rails, a cable member carried by said means, a winding shaft positioned between said standards and said member, a cable connected with 90 said winding shaft, passing around said member and said pulleys and connected with the front end of said body, and actuating means for said cable.

11. In a hoisting and dumping vehicle, the 95 combination with the chassis having side rails provided with longitudinally extending slots, of a body on said side rails, anti-friction devices between the rear end of said body and said side rails, bars connected with 100 said body, a shaft connected with said bars, anti-friction devices on said shaft and seated in said slots, standards rising from said chassis, pulleys on said standard, a winding shaft, a cable actuated by said winding shaft, 105 passing around said bar shaft, said pulleys and connected to said body at its front end, and actuating means for said cable.

EDWARD ALBRECHT.
